176,566

AIRCRAFT OR SIMILAR ARTICLE

Gerard J. Soucy, Dallas, Tex.

Application May 5, 1955, Serial No. 35,849

Term of patent 3½ years

(Cl. D71—1)

Figure 1 is a front elevational view showing my new design for an aircraft or similar article,

Figure 2 is a side elevational view thereof, and

Figure 3 is a top plan view.

I claim:

The ornamental design for an aircraft or similar article, substantially as shown.
